(57) **CLAIM**

The ornamental design for a peeler, as shown and described.

DESCRIPTION

FIG. 1 is a perspective view of the peeler;
FIG. 2 is an exploded perspective view of the peeler showing the pivoting cover, blades and peeler body;
FIG. 3 is a top plan of the peeler of FIG. 1;
FIG. 4 is a bottom plan view of the peeler of FIG. 1;
FIG. 5 is a front side view of the peeler of FIG. 1, with the rear side view being an identical mirror image;
FIG. 6 is a right side view of the peeler of FIG. 1;
FIG. 7 is a left side view of the peeler of FIG. 1;
FIG. 8 is a cross sectional view of the peeler taken along axis 8-8 of FIG. 6; and,
FIG. 9 is a bottom plan view of the peeler body.
The portions represented by broken lines form no part of the claimed design.
